Des. 183,978
Patented Nov. 25, 1958

183,978

COMBINED DESK AND CARD RACK

Harvey J. Smith, Greensboro, N. C.

Application January 7, 1957, Serial No. 44,419

Term of patent 14 years

(Cl. D33—7)

FIG. 1.

FIG. 3.

FIG. 2.

I claim:

The ornamental design for a combined desk and card rack, as shown.
